UNITED STATES PATENT OFFICE.

CHARLES E. AVERY, OF JERSEY CITY, NEW JERSEY, ASSIGNOR TO MANHATTAN ELECTRICAL SUPPLY COMPANY, OF NEW YORK, N. Y., A CORPORATION OF NEW JERSEY.

ELECTRIC HORN.

1,148,348.

Specification of Letters Patent. Patented July 27, 1915.

Application filed October 2, 1911. Serial No. 652,347.

To all whom it may concern:

Be it known that I, CHARLES E. AVERY, a citizen of the United States of America, residing at Jersey City, in the county of Hudson and State of New Jersey, have invented certain new and useful Improvements in Electric Horns, of which the following, is a specification.

My invention relates to electro-magnetically operated acoustic signaling devices, commonly termed electric horns, and in which there are combined an electromagnet, armature and diaphragm with a rod to impart the vibrating movement of the armature to the diaphragm.

The main object of my invention is to so construct the horn as to produce a louder and more penetrating acoustic signal than can be produced with horns of equal capacity as ordinarily constructed.

Other objects of my invention are to improve the details of construction of the contacts and connections, and also to adapt the horns for installation in factories and other buildings for fire or other alarm purposes.

In the accompanying drawings, Figure 1 is a section on the line 1—1, Fig. 3; Fig. 2 is an underside elevation, with the casing partly broken away; Fig. 3 is a section on the line 4—4, Fig. 2; Fig. 4 is an enlarged sectional view of the armature, diaphragm, and contact.

In the present instance the electromagnet is shown as consisting of four coils A, with cores secured to an iron base plate B which in turn is fastened by screws or otherwise to a flanged ring C of brass or other non-magnetic material, which may conveniently form a part of the casing. The rest of the casing in this instance comprises a sheet metal hood D inclosing the working parts and having secured to its outer closed end a flanged base plate E, by which the whole device may be secured to a wall or other suitable foundation. To the opposite ends of the cores of the electromagnet from those secured to the plate B is attached a supporting frame piece F of brass or other non-magnetic material to which are secured two opposite projections f. On these two opposite projections f I secure the opposite ends of a spring plate P which carries on its inner face a heavy weighted armature a, consisting, in this case, of three soft iron

plates united together. These armature plates are secured to the spring plate P by a rivet p, Fig. 4, which at the same time is used as a means of securing to the outer side of the spring P the contact plate G, with intermediate insulated washers g of mica or other suitable material, Fig. 4. To one end of this contact plate is electrically and mechanically secured the free end of a coiled spring H, whose opposite end is electrically and mechanically secured to an insulated binding post 6 for one of the circuit wires. The other end of the contact plate G is bent around into spring form to make and break contact with an adjustable set screw 7 in a cross bar 8 carried by, but insulated from, two posts 9 on the supporting plate F. This cross bar 8 is electrically connected to one of the circuit wires. Thus when the electromagnet is energized, the armature is attracted and the contact plate G breaks contact with the screw 7, breaking the circuit at that point, whereupon the electromagnet is deenergized and the spring plate P draws the armature back and completes the contact again at 7, whereupon the electromagnet is again energized and the armature attracted and the circuit broken as before.

To the same ring C which carries the electromagnet, but at some distance in front of it, is secured the diaphragm K, to which is attached a rod R extending back between the electromagnet coils to within a short distance of the armature,—such a short distance, in fact, that when the armature is attracted by the electromagnet the armature will strike the end of the rod and impart its vibrations to the latter and thence to the diaphragm. In front of the diaphragm is the usual amplifying mouth piece or horn M.

In horns as heretofore constructed, the armature-carrying spring has usually been mounted at one end only. By having a comparatively long spring plate P mounted at both ends, I am able to carry a relatively heavy armature and still maintain a high speed of vibration; the heavy armature enables me to get a hard blow at the diaphragm and so produce a louder and more penetrating noise.

The advantage of connecting the circuit wire to the contact plate G through the medium of a coiled spring H is that if the ordinary covered circuit wire were directly

connected to the contact plate, the repeated vibrations of the armature would gradually crystallize and finally break the wire.

While my horn is adapted for use on automobiles, boats and the like, it is also well adapted for use for fire alarm signals, especially in factories using noisy machinery, and where consequently a loud, penetrating acoustic signal is of great importance. It is for this purpose that I have constructed the inclosing casing with the supporting base plate E.

I claim as my invention,

1. An electromagnetic signaling horn, comprising an electromagnet, armature, diaphragm and means by which the movements of the armature may be imparted to the diaphragm, a spring plate supporting the

armature and a contact on the spring plate, a circuit wire and a spring connecting the circuit wire with the contact. 20

2. An electromagnetic signaling horn, having an electromagnet, an armature with a spring plate carrying the armature on one side, a contact also mounted on the spring plate on the other side, but insulated from it, and a rivet securing said armature, spring plate and contact together. 25

In testimony whereof I have signed my name to this specification, in the presence of 30 two subscribing witnesses.

CHARLES E. AVERY.
